UNITED STATES PATENT OFFICE.

FOSTER MILLIKEN, OF LAWRENCE, NEW YORK.

STREET-LIGHT.

1,264,114.

Specification of Letters Patent. Patented Apr. 23, 1918.

Application filed August 18, 1917. Serial No. 187,007.

To all whom it may concern:

Be it known that I, FOSTER MILLIKEN, a citizen of the United States, and a resident of Lawrence, in the county of Nassau and 5 State of New York, have invented a new and Improved Street-Light, of which the following is a full, clear, and exact description.

This invention relates to street lights and has for an object the provision of an improved construction, which may be used on 10 the street at any place and acts in the double capacity of a lighting device and signal device.

Another object of the invention is to provide a street signal light which will produce 15 flashes of light intermittently and thereby attracting the attention of persons passing the light.

A further object of the invention is to 20 provide an easily movable street light adapted to be placed at any point, as for instance, cross-roads in the country or cross-streets in towns, and by reason of its construction present proper signs for guiding 25 pedestrians and vehicles and at the same time give intermittent concentrated flashes of light.

In the accompanying drawings:

Figure 1 is a side view of a street lamp 30 embodying the invention.

Fig. 2 is a longitudinal vertical section through the lamp shown in Fig. 1, same being taken approximately on the line 2—2 of Fig. 3.

Fig. 3 is a transverse sectional view 35 through Fig. 2 on line 3—3.

Fig. 4 is a sectional view similar to Fig. 3, as shown in a slightly modified form of the invention.

Fig. 5 is a sectional view similar to Fig. 4 disclosing a further modified form of the invention.

Fig. 6 is a sectional view similar to Figs. 4 and 5, but disclosing a still further slightly 45 modified form of the invention.

Fig. 7 is a side view of the upper part of 50 a street lamp embodying the invention, certain parts being broken away for illustrating the construction, same illustrating a modified form of motor to that shown in Fig. 2.

Fig. 8 is a view similar to Fig. 7, but disclosing a further modified lamp arrangement and motor when electricity is utilized.

55 Referring to the accompanying drawing by numerals, 1 indicates a base to which a

supporting standard 2 is secured, this standard being preferably hollow, as well as the base, as shown in Fig. 2, in order to provide a strong, light construction. A plurality of 60 brackets or arms 3 are connected with the upper part of the standard 2 in any desired manner, said brackets having arranged thereon a casing 4 which may be of any material, as for instance, metal, and pressed 65 so as to produce an ornamental construction as shown in Fig. 3, though other shapes may be used without departing from the spirit of the invention. When the casing is made square, a glass panel 5 is arranged in each 70 side, each of the panels being provided with a pair of lenses 6 and 7 preferably connected to the glass panels, though separate lenses could be provided if desired. The lenses 6 and 7 are spaced apart the same 75 distance as the lamps 8 and 9 so that when the lamps are in the position shown in Fig. 2 a concentrated or very brilliant light will be projected through the lenses 6 and 7, which preferably are red for indicating danger and attracting the attention of persons 80 passing. For the sake of cheapness in construction the various panels or panes 5 may be flat sheets of glass, ground glass being 85 preferable, while the lenses 6 and 7 may be 85 separate members secured in any suitable manner to the panes 5 or supported adjacent said panes, substantially as shown in Fig. 1. Arranged in the casing 4 (Fig. 2) are oil 90 burning lamps 8 and 9 provided with a common tank 10, though an independent tank could be provided if desired. It will also be evident that other forms of lamps 95 may be used, as for instance, electric lamps, as hereinafter fully described. A double faced reflector 11 is preferably arranged between the lamps so that when they are turned in a position at right angles to that shown in Fig. 2 there will be no shadow cast by one lamp on the other, whereby 100 proper illumination of the entire casing is provided in addition to producing comparatively dull red sections caused by the lenses 6 and 7, which lenses may be red in themselves or may have coloring matter connected therewith, or arranged so that the rays 105 of light passing through the lenses will pass through the coloring matter. The tank or container 10 shown in Fig. 2, is mounted on a suitable turn-table 12 connected in any 110 suitable manner with a motor 13 of any desired type, as for instance, a spring motor,

though an electric or weight motor could be used without departing from the spirit of the invention. This motor is preferably made of a size to run continuously for ten or twelve hours, though a stronger or weaker motor may be used if preferred. The intention is to start the motor going at dusk and to regulate the motor so that the lamps 8 and 9 will turn slowly all night whereby 10 there will be a bright flash of red light whenever the respective lamps are directly in line with the lenses 6 and 7. It will be observed that the red light will be flashed in opposite directions simultaneously, so that 15 there will be a flash of red light upon each half revolution of the turn-table 12. At the upper part of the casing 4 is arranged a sign 14, with the word "Go" on two wings and on other wings the word "Stop" or any 20 other legend. This structure is adapted for city use where a traffic officer is provided to turn the sign for indicating which street is closed. It will be observed that the lamps 8 and 9 are inclosed in the casing 4 so the 25 wind, rain and the like cannot effect the same, openings 15 being provided at the top for ventilation, while suitable openings 16 and 17 are provided at the bottom where air enters to cause a proper combustion. It 30 will be noted that the lamps produce an illumination of the street surface in addition to producing the flashes of red light. The various panes of glass 5 are provided with signs of any suitable kind, as for instance, 35 the name of the street and an order, as for instance, "Keep right," as illustrated in Fig. 1. One of the panes 5 is mounted in a door frame 18 which is supported by suitable 40 hinges 19 and held normally closed by a catch 20. This permits ready access to the lamps while not in any way disturbing or changing the appearance of the complete light. The lenses 6 and 7 are spaced a short 45 distance apart, namely the same distance as the lamps 8 and 9 and are in horizontal line substantially centrally of the pane of glass, but it is evident that these lenses could be differently arranged if desired. To augment or to make more effective the illumination 50 of the street by the lamps 8 and 9 the interior surface 21 of the casing is made from some bright material, and if desired may be supplied with reflectors.

Referring particularly to Fig. 4, it will 55 be seen that on opposite sides of each of the lamps 8 and 9 are arranged lenses 22 and 23, said lenses being supported upon the container 10, although they may be supported in a suitable manner on the interior 60 without departing from the spirit of the invention. Arranged on each of the panes of glass 5 are sections 24 of red matter which may be painted on to the glass, formed in the glass, or applied in any desired manner so as to produce a section 65

through which the concentrated rays from the lenses 22 and 23 will pass for producing concentrated rays of red light at certain intervals as the lamps move. In addition to producing intervals of bright red sections on the panes of glass 5, lenses 22 and 23 will produce continuous concentrated rays moving in a circle so that in addition to the general illumination produced by the lamps 8 and 9, these streams of concentrated rays 70 of light will give the device a distinctive character which will compel the attention of any passing the device. It will thus be seen in this form of the invention the same flashes of intermittent red light will be produced and in addition rays of concentrated 75 light will be produced moving in a circle. 80

In Fig. 5 a further modified form of the invention is disclosed wherein the container 10 carries reflectors 25 and 26, while the panes 5 carry lenses 6 and 7 in a similar manner to that shown in Figs. 1 and 3, but these lenses may either be colored or may have coloring matter adjacent thereto, so that all rays of light passing therethrough 90 will be colored, as for instance red. As the lamps 8 and 9 move in a circle there will be produced an intermittent or winking light on the different sides of the casing 4. When the parts are arranged as shown in 95 Fig. 5 a concentrated ray of red light will be projected through one lens in one face of the device, and a concentrated ray of red light projected through another lens in the opposite face of the device and at substantially the opposite corner. 100

In Fig. 6 a further modified form of the invention is shown in which the lenses 6 and 7 are arranged on the chimneys 27 and 28, which chimneys are preferably frosted 105 or ground. The lenses in this instance may be made separate and connected to the chimneys, or made integral with the chimneys and either colored or uncolored. It the lenses are not colored coloring matter 110 29 is arranged at different points on the panes 5 so as to produce substantially the same effect as produced for instance in the form shown in Fig. 1. 115

As heretofore stated a spring motor 13 is provided for rotating the table 12 in the preferred form, but it is evident that any other desired motor could be used without departing from the spirit of the invention, as for instance a weight motor 30 can be 120 provided as shown in Fig. 7, the weight 31 extending into the hollow standard 2. Whenever desired electric current could be used and the lead-in wires 32 and 33 may pass up through the hollow post 2, connected at binding post 34 to the electric motor 35 and at 36 to brushes which connect with the slip rings 37 and 38, said slip rings being connected in turn with the filaments 125 of lamps 39 and 40. 130

It is to be understood that any form of motor may be used with any form of light and other arrangements of lenses and coloring matter may be utilized in addition to the modified ways of arranging the lenses and coloring matter shown, without departing from the spirit of the invention, as the above forms are given in the way of illustration of the inventive idea and not as the only means of producing flashes of light either clear or colored.

What I claim is:

1. A street light of the character described, comprising a casing having a plurality of windows, a pair of lenses arranged in each window, all of the lenses being in the same horizontal plane, a pair of lamps, and means for moving said lamps in a horizontal plane, and opposite said lenses intermittently.

2. In a street lamp of the character described, a casing having a window therein, a pair of spaced lenses arranged adjacent said window positioned in a horizontal plane, a pair of lamps spaced apart an equal distance to the distance between the lenses, and a horizontal supporting rotatable member for said lamps whereby said lamps will be brought alternately opposite said lenses and alternately to a position in line with the center between said lenses.

3. In a street lamp of the character described, a casing provided with a plurality of panes of glass, a lamp arranged in said casing, means for causing said lamp to move in a circle, and spaced fixed means associated with each of said panes of glass for concentrating the rays of light from the lamp when it reaches a predetermined position for producing a concentrated flash.

4. In a street light of the character described, a casing provided with a plurality of panes of glass facing in different directions, a lens arranged adjacent each pane of glass, a lamp arranged in said casing, and means for moving said lamp in a circle so as to pass successively said lenses and give a concentrated flash.

5. In a street light of the character described, a casing provided with a plurality of panes of glass facing different directions, a pair of spaced lenses arranged in a horizontal plane positioned adjacent each of said panes of glass, a pair of spaced lamps arranged in the casing, said lamps being spaced the same distance apart as the lenses, and means for causing the said lamps to move in a circle whereby intermittent flashes of light will be produced by said lenses.

6. In a street light of the character described, a casing provided with a plurality of panes of clear glass facing different directions, a pair of spaced colored lenses arranged adjacent each of said panes of glass, a pair of spaced lamps arranged in said cas-

ing, a double reflector arranged between said lamps, and means for causing said reflector to rotate and the lamps to move in a circle whereby will be produced intermittently a bright colored light projected through the lenses and a continuous illumination of all of the panes of glass in said casing.

7. A street light of the character described, comprising a casing having a plurality of windows, a pair of lamps, a rotatable support for said lamps whereby said lamps are moved in a circle, and colored lenses mounted at different points in said casing whereby when the light is in operation intermittent colored streams of concentrated light will be produced.

8. A street light of the character described, comprising a casing having a plurality of windows, a pair of lamps arranged in said casing, a rotatable supporting member for moving said lamps in a circle, a lens for each of said lamps, said lenses being on opposite sides of the lamps so as to project concentrated rays or streams of light in opposite directions, and coloring matter adjacent each of said lenses, whereby as the lamps move, oppositely extending streams of colored light will be produced intermittently.

9. A street light of the character described, comprising a casing having a plurality of windows, a rotatable platform arranged in said casing, a pair of lamps mounted on said platform, a pair of lenses arranged on each of said windows spaced an equal distance apart to the lamps, and a double faced reflector arranged on said platform between said lamps, whereby there will be provided a stream of light from opposite lenses at a given time for each lamp.

10. A street light of the character described, comprising a casing having a plurality of faces supplied with panes of glass, said panes being ground, a rotatable platform arranged in said casing, a pair of lamps arranged on said platform, and a pair of lenses arranged adjacent each of said panes of glass, said lenses being spaced substantially the same distance apart as the lamps.

11. A street light of the character described, comprising a casing having a plurality of substantially vertical faces, each face being provided with a ground glass pane, a lens arranged adjacent each of said panes and positioned to direct rays of light in a horizontal direction, a rotatable platform arranged in said casing, a lamp arranged on said platform positioned to move in a circle when the platform rotates, whereupon a stream of concentrated light will be projected through said lenses as the lamp moves past, and means for continuously rotating said platform.

12. A street light of the character described, comprising a casing having a plurality of faces, a pane of glass arranged in

each of said faces, a pair of lenses arranged adjacent each of said panes of glass, a sheet of coloring matter arranged adjacent each of said lenses, a rotatable platform arranged in said casing, and lamps arranged on said platform so as to move in a circle, said lamps being spaced apart substantially the same distance as said lenses.

13. A street light of the character described, comprising a casing having a plurality of faces, a pane of glass in each face, a pair of lenses arranged adjacent each of said panes of glass, coloring matter ar-

ranged adjacent each of said lenses, a rotatable platform arranged in said casing, and 15 a pair of lamps arranged on said platform and spaced apart substantially the same distance as said lenses, and a reflector arranged adjacent each of said lamps, the reflector of one lamp being diagonally opposite the reflector of the other lamp so that the lamp will project rays of light through the lens on one of said faces and the other lamp will project rays of light through the lens on the opposite face. 20

FOSTER MILLIKEN.
